STEAM BOILER

Isaac Goldberg, Los Angeles, Calif., assignor to
Master Steam Equipment Company, Los Angeles, Calif., a corporation of California

Application September 3, 1937, Serial No. 162,266

1. Claim. (Cl. 122—250)

Many different types of water-tubular coil boilers have been designed but the difficulty in most of these designs has been the tendency to burn out the tubes, partly due to poor water circulation, and partly due to the fact that it is nearly if not quite impossible to readily clean the tubes of mud and scale.

The purpose of my invention is to provide a type of boiler that will be free from the above 10 defects, particularly in the provision for quick and thorough cleaning of the coils. A further purpose of my invention is to provide a system of coils which can be quickly disconnected and replaced with a minimum of time and expense. 15 My invention is specifically designed to be used in boilers of comparatively small horse-power, although there is no reason why large boilers cannot be constructed employing the improvements which my invention includes.

20 I illustrate my invention by means of the accompanying drawings in which: Figure 1 is a side elevation of my device equipped with a single set of coils, having the side wall of the casing removed and the coils shown in section. Figure 2 is a plan view of the gas burners. Figure 3 is a side elevation of my device equipped with two sets of coils, also with the side wall removed. Figure 4 is a plan view of one of the coil sets and its header. Figure 5 is a front elevation of 30 the header and coils. Similar numerals refer to similar parts in the several views.

The construction of my device is as follows: 10 is a casing enclosing the boiler proper and which can be provided with insulated heat-resisting walls if desired. The front may also be provided with suitable doors through which access 35 can be had to the interior. Near the base of the casing is a gas burner which may consist of the hollow metal gas distributor 11 which is supplied 40 with gas by means of suitable conduits 12 and having attached to its upper surface a plurality of upright Bunsen burners 13. The burner shown and described is conventional only, and other burners for gas or other fuel may be substituted 45 if desired without departing from the spirit of my invention. The flow of gas to these burners may be controlled by suitable thermostatic or pressure automatic regulators if desired. 14 shows a means for attaching a pressure regulator. 50 Located above the said burners or their equivalent is a group of conduit coils nested with each other, the largest in diameter 15 being the outer coil of the group and having within its circular confines a similar coil 16, another still smaller in 55 diameter 17 and an inner coil 18 which is the

smallest of the group. The number of such coils in the group may be varied to suit the size and design of the boiler. It will be noted that the end 19 of each of these coils is brought out a short distance from the periphery of the coil of which it is a part, and tangent to its circular form. These ends from the upper portion of the coils extend in a horizontal plane toward a hollow metal header 20, the ends 21 extending from the lower end of the said coils extend in a horizontal plane toward a similar header 26. All of these extended ends of the coils are provided with couplings 22 so that the extended ends may be sufficiently short as to permit the coils to be assembled one within the other without the ends 10 interfering with such assembly. Connected to each of the couplings 22 are nipples 23, having on their outer ends unions 24 and nipples 25, extending from the said unions to the upper or lower header 20 or 26 respectively, and connected 15 thereto by convenient means such as being screwed into the header. On the opposite side of the said headers and opposite to each of the conduit connections from the coils is another opening, into each of which is secured the nipple 27 of sufficient length to extend through the wall 10 of the casing where it is closed by a cap 28 or by other suitable removable means. The headers 20 and 26 may be made in one casting as shown if desired, or other suitable means of supporting and connecting the said headers may be used. Means for the introduction of water into the boiler may consist of a suitable conduit 29 from a source of water supply such as a pump. This pump is not shown in the drawings, as any 30 type of water feed may be used. The conduit 29 connects the source of water supply with the under side of the lower header 26 and is also connected directly to the steam drum 30. If desired a water-level control may be used which is shown 35 conventionally at 42, and which could be connected to the water supply conduit 29 and to the steam drum 30, and also provided with a float and a water gauge 32. Above the coils is a steam drum 30 which is connected to the upper side of 40 the header 20. The boiler is also provided with the usual attachments such as steam gauge 33, the safety valve 34, a filling pipe 35, a main discharge steam pipe 36 and a vent or stack 37 is provided in the top of the casing. A blow-off 45 cock is also provided.

The duplex type shown in Figure 3 is very similar to the single coil type. In this type there are two groups of coils located back to back, each with its own upper and lower header. The 55

headers 38 of one group of coils are adjacent to the front wall of the casing 10, and the headers 39 of the other group of coils are adjacent to the rear wall of the casing 10. The extended nipples 27 extending outwardly from the headers, pass through the front and back wall of the casing 10 and are provided with caps 28 or other suitable removable closure. In either type suitable supports are provided for locating and carrying the weight of the coils.

The principal purpose of my invention is to provide a water-tube boiler which will give a maximum life to the tubular coils and provide for the quick and convenient cleaning of the said coils thus preventing the scaling and mud burning of the coils. In order to clean the coils it is only necessary to unscrew the caps 28 and connect them with a source of water supply which may be chemically treated if desired.

It will be noted that the circulation of water in the boiler is through the conduit 29 from the pump to the lower header, through this header and into the coils by means of the nipples 25, the unions 24, the nipples 23 and the couplings 22. The water flows upwardly through the coils, reaching the upper header by means of the upper couplings 22, the nipples 23, the unions 24 and the nipples 25. From the upper header the steam and water flows upwardly into the steam drum 30. In the duplex type the flow of water is the same but flows through both coil groups simultaneously, into a common steam drum. The water level in the drum is preferably as shown by the dotted line 31.

It will be noted that a further improvement is attained by extending the pipes 45, connect-

ing the headers with the steam drum 30, upwardly above the water level, while the pipes 43 and 44 from the water supply pipe 29 to the said drum end at a point below the water level in the said drum. The object of this arrangement is that when blowing off the boiler or washing out the steam drum, the mud and scale which has accumulated along the bottom of the drum will be washed out through the pipes 43 and 44 and not through the headers of coils. These pipes also add greatly to the rapid circulation of the water and steam in the boiler.

What I claim as my invention and desire to secure by Letters Patent is:

In a device of the class described, the combination of a case containing a group of spirally-coiled water-tubes, said coils being nested within one another and adapted to be heated by suitable heating means; a lower header connected to a source of water supply, said header also being connected to the lower ends of the said coils; an upper header connected to the upper ends of the said coils; a steam drum connected to the said upper header; means for detaching any one of the said coils from both of the said headers and from the other coils of the group, said means consisting of the lower and upper ends of each coil being extended tangentially to the said coil and having a coupling and union in the conduit between the said coil and the said header; and means for cleansing said coil, said means consisting of clean-out tubes extending from the headers to a point outside of the said case and located opposite each of the said coil connections.

ISAAC GOLDBERG.
